[57] **CLAIM**

The ornamental design for a combined pillow cover and photograph holder, as shown and described.

DESCRIPTION

FIG. 1 is a perspective view of a combined pillow cover and photograph holder, showing our new design;

FIG. 2 is a front elevational view;

FIG. 3 is a side elevational view, all sides being substantially identically thereto;

FIG. 4 is a side elevational view showing a second embodiment provided with a vertical photo holder of our new design, all sides being substantially identically thereto; and, FIG. 5 is a front elevational view showing a third embodiment provided with an oval photo holder.

The rear of the article forms no part of the claimed design. The broken lines are for environmental purposes only and form no part of the claimed design.
